Primary Examiner — Abraham Bahta(74) *Attorney, Agent, or Firm* — Eric Karich; Karich & Associates(57) **CLAIM**

The ornamental design for a “food dispensing pouch,” as shown and described.

DESCRIPTION

FIG. 1 is a top plan view of a food dispensing pouch, showing my new design; and,
FIG. 2 is a rear perspective view thereof, illustrating a rear opening in an open configuration.

1 Claim, 2 Drawing Sheets*Fig. 1*

Fig. 2
